[57] **CLAIM**

The ornamental design for a tennis racket, as shown and
described.

DESCRIPTION

FIG. 1 is a perspective view of a tennis racket showing
my new design;

FIG. 2 is a front elevational view thereof, the side oppo-
site being a mirror image;

FIG. 3 is a side elevational view thereof, the side oppo-
site being a mirror image;

FIG. 4 is a top plan view thereof; and

FIG. 5 is a bottom plan view thereof.

For ease of illustration portions of the strings have been
omitted from FIGS. 1 and 2.
